UNITED STATES PATENT OFFICE.

FRANZISKA MÜLLER, OF ATLANTIC CITY, NEW JERSEY.

HAIR WAVER OR CURLER.

1,241,240.

Specification of Letters Patent. Patented Sept. 25, 1917.

Application filed October 2, 1916. Serial No. 123,273.

To all whom it may concern:

Be it known that I, FRANZISKA MÜLLER, a citizen of Germany, and resident of Atlantic City, N. J., have invented certain new 5 and useful Improvements in Hair Wavers or Curlers, of which the following is a specification.

The present invention relates to improvements in hair wavers or curlers, and particularly such devices for imparting to ladies' hair the so-called "Marcel" wave. Heretofore the services of experts have been required to prepare the hair in this attractive manner, which was not only expensive and 10 time consuming, but was very often inconvenient. In fact, when a lady desired to have her hair dressed in this particular style for an evening function, for instance, it was necessary that she either go to the expense 15 of having a hair dresser come to her home, or spend a part of the afternoon prior to the function in a hair-dressing establishment, the hair often becoming disarranged during the intervening time before the function. 20 Such difficulties it will be seen, prohibited many women from wearing their hair in this very attractive style.

The present invention is intended to overcome these difficulties, and provides a waver 30 which may be successfully and conveniently used at home, and without aid. Also it is proposed to provide such a device which may be satisfactorily used by a novice, and will produce as perfect a Marcel wave as could 35 only be produced by experts heretofore. A further object is to provide such a device which will be simple in construction and inexpensive to manufacture.

With these and other objects in view my 40 invention is shown in the accompanying drawings, and will be hereinafter more fully described with reference thereto and finally pointed out in the claims.

In the accompanying drawings,

45 Figure 1 is a front view of one form of my improved invention.

Fig. 2 is a side view thereof in closed position,

Fig. 3 is a similar view in open position,

50 Fig. 4 is a front view of a slightly modified form of construction.

Fig. 5 is a sectional view taken on the line 5—5 of Fig. 1 with parts omitted.

55 Fig. 6 is a sectional view taken on the line 6—6 of Fig. 4 with parts omitted,

Figs. 7 and 8 are front views of the parts making up my first form of invention,

Figs. 9 and 10 are similar views of the parts making up the modified form thereof, and

60 Fig. 11 is a side view of the matrix member.

Similar reference characters indicate corresponding parts throughout the several figures of the drawings.

65 Referring first to Figs. 1, 2, 3, 5, 7 and 8, I show a construction made according to my invention, and comprising a plate or matrix member 20, hinged to a fork member 26. The matrix member 20 has contiguous longitudinally extending portions 21 which are transversely curved in a way that presents convex surfaces on one side of the matrix member and concave surfaces on the other.

The convex surfaces are turned toward the 70 observer in Figs. 1 and 8. When viewed edgewise, or in section, the matrix member will thus present a plurality of arches, as seen in Fig. 5. Between each pair of adjacent portions 21, there will be a longitudinally 75 extending recess or depression and the opposite longitudinal edges of the member 20 will be bent toward the side or face of this member which presents the convex surfaces above referred to, so as to provide similar 80 longitudinally extending recesses or depressions.

To the member 20 is secured a handle 22 by suitable fastening means, such as rivets 23. This handle has a hinged portion 24. The fork member 26 is also provided 85 with a handle 25 having hinged member 27 to coöperate with the hinged portion 24 of the handle 22, and a pivot member 28 may be used to engage the portions 24 and 27, and connect the handles 22 and 25 together 90 in the required manner. The fork member 26 will be provided with prongs 30 equal in number to the longitudinally extending recesses or depressions of the member 20, and these prongs will preferably be triangular in 95 cross section, so as to fit into these recesses or depressions of the matrix member 20.

Between two of the prongs of the fork, adjacent the base of the same, is a curved piece of metal 29, fixed in place, and intended to serve the purpose of a stop to prevent the hair from getting too close to the hinge between the fork member and the matrix member. Adjacent element 29 the matrix member will have its edge recessed so as not 100

105

110

to obstruct this element 29 when the fork and the matrix member are moved together. This recess, of a shape corresponding to that of the stop 29, as shown in Figs. 1 and 8, is 5 formed at that edge of the left-hand member 21 which is nearest the handle. The corresponding edge of the right-hand member 21 is projected or bulged toward the handle, and the fork member 26 is correspondingly 10 recessed between the prongs 30, as shown at 26', so that the said bulged edge portion of the right-hand member 21 can pass between the respective prongs 30. At the edge farthest away from the handle, the arrangement is reversed, that is, the edge of the left-hand member 21 is projected lengthwise or bulged, and the edge of the right-hand member 21 is recessed, so that the two members 21 are of equal length, notwithstanding the 15 recesses and bulges at their edges.

In operation, the waver is heated to the required extent and then opened by means of the handles 22 and 25. The fork is then thrust into the hair so as to get as many 25 strands as required between the fork member and the matrix member; whereupon the handles 22 and 25 are pressed together. The prongs of the fork fit snugly into the longitudinal recesses or depressions in the matrix member, and draw the hair tightly against the convex surfaces of the portions 21, giving to the hair the undulations known as the Marcel wave. After the operation is finished, the fork is opened and removed. The 30 function of the element 29 is to prevent any of the hair from getting too far toward the hinge connecting the handles 22 and 25, as to be out of position to be engaged by the matrix member. Of course, the foregoing 35 operation can be repeated as often as necessary, until the hair has the appearance required. The waver will neither stretch, break nor tangle the hair.

In the modification shown in Figs. 4, 6, 45 9, 10 and 11, the number of convex portions of the matrix member and the number of prongs on the fork are increased. The matrix member is indicated by the numeral 40, and is secured to a handle 41; which is 50 fixed to the middle convex portion. At 43 is indicated the fork member having forks 43' and carrying an element 42 similar to the element 29. I prefer to curve the handle 44, as shown in Fig. 11 so as to make room 55 for this element 42 and the inner end of the member 40 is recessed; so as not to obstruct the element 42 when the handles of the fork member and the matrix are pressed together.

60 It will be seen that both forms of hair waver which I have above described are relatively flat, and both are operated in the same way. When the matrix member and fork member are pressed together, the element 65 29 will extend past the convex face of the

adjacent portion 21, toward the opposite face; and thus effectually arrest any strands of hair that might tend to work down in the waver beyond the inner end of the member 20, and thus get out of position to be 70 engaged by the waver and caused to set into the shape required.

Obviously it is necessary only that the portions 21 be convex on their faces which are presented toward the fork 26; and they 75 need not be concave on their opposite faces. They are shown as concave on their opposite faces only because it is convenient to make the members 21 have convex faces by stamping the member 20 out of a piece of metal. 80 The essential feature of the construction of my hair waver resides in a matrix member having a convex portion with longitudinal grooves along the sides of this portion to receive the prongs of the fork in the manner 85 above described.

I have illustrated and described preferred and satisfactory forms of my invention, but it is obvious that changes may be made therein within the spirit and scope thereof, 90 as defined in the appended claims.

I claim:

1. In a hair waver, a matrix member, comprising a plurality of arches having recesses therebetween and at the sides, a fork member 95 having prongs corresponding in number to said recesses and adapted to fit into said recesses, handles on said matrix member and fork member, and means pivotally connecting said handles.

2. In a hair waver, a matrix member, comprising a plurality of arches having recesses therebetween and at the sides, a fork member having prongs corresponding in number to said recesses, V-shaped in cross-section 105 and adapted to fit into said recesses, handles on said matrix member and fork member, and means pivotally connecting said handles.

3. In a hair waver, a matrix member comprising a plurality of longitudinally extending contiguous portions which have convex surfaces facing in the same direction, each of said portions being separated from an adjacent portion by a longitudinal depression, the matrix member having similar 110 longitudinal depression, the matrix member having similar longitudinal depressions adjacent its opposite longitudinal edges, and a fork member connected to the matrix member and having prongs adapted to fit into 115 said depressions, whereby, when the hair is engaged by the waver, the prongs will dispose the hair smoothly across the said convex faces of said portions.

4. In a hair waver, a matrix member comprising a plurality of contiguous longitudinally extending portions which are convex on one face, each of said portions being separated from the adjacent portion by a longitudinally extending depression, said member 120

having similar longitudinal depressions adjacent its opposite longitudinal edges, a fork connected to the matrix member and having prongs adapted to fit said depressions, 5 whereby, when hair is engaged by said waver, said prongs will dispose the hair evenly over the convex faces of said portions, and a stop member carried by said fork adjacent the prongs thereof, the matrix 10 member being recessed opposite said stop member.

5. In a hair waver, composed of a matrix member and a fork member, both formed with handles and connected pivotally, said 15 matrix member comprising longitudinally-extending contiguous portions which have convex surfaces facing in the same direction, adjacent convex-surfaced portions being separated by a longitudinal depression, the matrix member having similar longitudinal depressions adjacent its opposite longitudinal edges, and that edge of the 20 matrix member which is nearest the handle being recessed at one of said portions and projected toward the handle at the adjacent portion, while the reverse arrangement obtains at the edge farthest away from the handle, and the fork member having prongs 25 adapted to fit into said depressions.

30 6. In a hair waver, a matrix member comprising a longitudinally extending portion which is convex on one face, said member having longitudinal depressions extending along the sides of said portion, and a fork

connected to the matrix member and having 35 prongs adapted to fit said depressions, whereby, when the hair is engaged by said waver, said prongs will dispose the hair evenly over said convex face, and a stop member carried by said fork adjacent the 40 prongs thereof, the matrix member being recessed opposite said stop member.

7. In a hair waver, composed of a matrix member and a fork member, both formed with handles and connected pivotally, said 45 matrix member comprising longitudinally-extending contiguous portions which have convex surfaces facing in the same direction, adjacent convex-surfaced portions being separated by a longitudinal depression, the 50 matrix member having similar longitudinal depressions adjacent its opposite longitudinal edges, and that edge of the matrix member which is nearest the handle being recessed at one of said portions and projected toward the handle at the adjacent portion, and the fork member having prongs 55 adapted to fit into said depressions, and a curved stop arranged to register with said recessed edge portion of the matrix member. 60

In testimony that I claim the foregoing as my invention, I have signed my name in presence of two subscribing witnesses.

FRANZiska MÜLLER.
